(57) **CLAIM**

I claim the ornamental design for a housing for an automotive differential, as shown and described.

DESCRIPTION

FIG. 1 shows a top front perspective view of a housing for an automotive differential showing my new design;

FIG. 2 shows a top back perspective view thereof;

FIG. 3 shows a bottom back perspective view thereof;

FIG. 4 shows a back view thereof;

FIG. 5 shows a front view thereof;

FIG. 6 shows a top view thereof;

FIG. 7 shows a bottom view thereof;

FIG. 8 shows a left view thereof; and,

FIG. 9 shows a right view thereof.

The broken lines in the figures illustrate portions of the housing that form no part of the claimed design.

1 Claim, 5 Drawing Sheets
